UNITED STATES PATENT OFFICE.

ARTHUR A. JOHNSON, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,323,287.

Specification of Letters Patent.

Patented Dec. 2, 1919.

Original application filed June 23, 1917, Serial No. 176,488. Divided and this application filed May 11, 1918.
Serial No. 233,848.

To all whom it may concern:

Be it known that I, ARTHUR A. JOHNSON, a citizen of the United States, residing in borough of the Bronx, in the county of the Bronx, city and State of New York, have invented certain new and useful Improvements in Type-Writing Machines, of which the following is a specification.

This invention relates to typewriting machines, and more particularly to paper-feeding mechanism therefor.

This application is a division of my application Serial No. 176,488, filed June 23, 1917.

15 A feature of the present invention is the provision of means for facilitating the manipulation of work-sheets in a typewriting machine, so that the sheets may be speedily inserted and accurately located at the proper 20 place to receive the typewriting operations, and also may be easily withdrawn preparatory to the writing of the next form.

To do this, the platen of the machine is provided with a driving member which is 25 connected thereto to rotate the platen major amounts. This driving member preferably comprises a gear-segment which is constantly in mesh with a gear carried by the platen axle. This gear-segment may be 30 provided with a handle, by means of which the same may be rotated, either forwardly to advance the work, or rearwardly to facilitate manipulating or withdrawing the work from the platen.

35 In order to accurately locate the sheets at proper position to commence writing, when again advanced by the operation of the driver handle, the present invention provides a stop-mechanism which is normally 40 ineffective to arrest the platen, but which is brought into operation automatically as the driver is rapidly pulled forward. This stop-mechanism may comprise a plunger carried by the driver, and having at one end 45 a stop and at the other end a cam member, which engages a cam carried by the frame. The movement of the cam member past the cam frame causes the plunger to move the stop to position to engage a stop that is fixed 50 to the frame, and thus arrest the driver. The movable stop strikes the fixed stop after the cam on the plunger has moved past the fixed cam. Thus, when the arrested handle is released by the operative, the stop is re-

turned by its spring to ineffective position, 55 where it does not interfere with the feeding of the work by the usual line-space mechanism, or by the usual finger-piece on the platen axle. The cam on the frame is pivotally mounted to permit the free passage 60 of the driver in one direction.

Other features and advantages will hereinafter appear.

In the accompanying drawings,

Figure 1 is a plan view, showing my device as applied to an Underwood typewriting machine.

Fig. 2 is a side view of the parts shown in Fig. 1, the hand-crank being shown in its rearmost position in broken lines.

Fig. 3 is a front elevation of the parts shown in Figs. 1 and 2, showing the handle as released by the operative after its arrest by the stop-mechanism of the present invention.

Fig. 4 is an enlarged detail view showing the parts in arrested position, the movable stop being held to the fixed stop by frictional engagement therewith due to the operative's pressure on the crank-handle.

The platen 1, which carries interleaved carbon and work-sheets to effect a typewriting operation, is secured to an axle 2 mounted to rotate in a platen frame 3, which is mounted in the usual manner on the typewriter carriage. The platen 1 may be line-spaced in the usual manner by means of a line-space lever 4, which advances the platen line-space intervals, carrying with it the work and carbon-sheets.

In order that the pack comprising the work and carbon-sheets may be gripped to the platen 1, so as to feed therewith, there are provided pressure feed-rolls 5 and 6 of the usual type.

In addition to driving the platen 1 by the line-space lever 4, it may also be driven both reversely and in an advancing direction a major amount, so as to withdraw the pack of work-sheets and carbon-sheets to permit their displacement, and return them to the platen. For this purpose, the platen axle 2 is provided, at one end, with a pinion 7 arranged to be engaged and driven by a gear-segment 8. The gear-segment 8 is mounted on a hand-crank 9 pivoted intermediate its ends at 10 in a bracket 11, secured to the end plate 3. The hand-crank 9 is provided

with a handle 12, which, when pulled forwardly, moves the platen 1 and the work carried thereby in advancing direction, and, which, when pushed rearwardly moves the 5 platen and work rearwardly.

The hand-crank 9 is moved from the dotted-line position in Fig. 2, to the full-line position in said figure, for the purpose of bringing the first line to be written upon 10 on the work-sheets into printing position.

In order to speedily and accurately locate the initial writing line on the work-sheet at the printing line of the machine, the present invention provides a stop-mechanism for 15 the hand-crank 9, which is automatically brought into operation at the proper time to accurately arrest the hand-crank when the work is in proper writing position. This stop comprises a plunger 13 guided against 20 rotary movement and sliding through the body portion of the gear-segment 8. On one end, the plunger 13 is provided with a head 14 normally held clear of a fixed stop 15 by means of a spring 16. During a forward 25 movement of the upper end of the hand-crank 9 to advance the platen, the other end of the plunger brings a cam surface 17 thereon into engagement with a cam surface 18 of a one-way acting tappet or dog 19, 30 which is mounted on the frame 3. The relative position of the dog 19 and the stop 15 is such that as the hand-crank 9 is swung with a quick motion, the plunger will be projected by the dog 19, so that its head 35 or stop 14 will engage the fixed stop 15 before the spring 16 can return the plunger, which has cleared the dog 19, to its normal position. When the stop 15 is struck by the hand-crank 9 the operative knows that the 40 work-sheets and carbon-sheets are properly positioned for the initial line of writing. The dog 19 is pivotally mounted on a support 20, so that it will yield when the abrupt face 13^a of the plunger 13 engages the 45 abrupt face 19^a of the dog 19. A spring 21 will return the dog 19 to its normal position after the plunger 13 has escaped past the dog.

After the crank 9 is stopped by the head 50 14 striking against the fixed stop 15, the operative releases the handle 12 and proceeds to typewrite. The release of the handle 12 permits the head 14 of the stop to be moved by its spring 16 away from the fixed 55 stop 15 to which it is held before the release of the handle 12 by frictional contact therewith. When in its arrested position, the cam portion 17 is located sufficiently past the dog 19, to be free to move to normal position 60 without interference from the latter. Thus, after the handle is released this stop-mechanism in no way interferes with the rotation of the platen either by the usual line-space mechanism 4 or by the finger- 65 pieces 20^a secured to the platen axle 2.

Variations may be resorted to within the scope of the invention, and portions of the improvements may be used without others.

Having thus described my invention, I claim:

1. The combination, with a revoluble platen and means for guiding work sheets thereabout, of a quick feed mechanism comprising a driving element having a rotatable connection with said platen and an 70 automatic stop mechanism for bringing said platen to rest at the end of a quick feed movement of predetermined extent by temporarily arresting said driving element at an intermediate point in its effective 75 range of movement, said stop mechanism being also self releasable so as to permit further feeding movement of said platen in the same direction after thus limiting the extent of a quick feed. 80

2. The combination with a platen, of a hand-crank for rotating said platen, a plunger carried by said hand-crank, a stop for interrupting the movement of said hand-crank and said platen by obstructing said 90 plunger, and a dog located to force said plunger into obstructing relation with said stop, intermediate the limits of travel of said hand-crank. 85

3. The combination with a platen, of a hand-crank for rotating said platen, a plunger carried by said hand-crank, a stop for interrupting the movement of said hand-crank and said platen by obstructing said 95 plunger, a dog located to force said plunger 100 into obstructing relation with said stop, intermediate the limits of travel of said hand-crank, and means for automatically clearing said plunger from said stop after it has passed said dog when the driving pressure 105 on said hand-crank is relieved.

4. The combination, with a revoluble platen, means for guiding work sheets thereabout and means for line spacing the same, of a quick feed mechanism comprising a 110 driving element having a rotative connection with said platen, and a normally ineffective stop mechanism capable of being rendered effective to arrest said driving element at a predetermined point in its movement when manipulated rapidly to effect a quick feed of said platen, said stop mechanism being self releasable at the end of such manipulation to permit further feeding movement of said platen and its connected 120 driving element in the same direction after thus determining the extent of the quick feed. 115

5. The combination, with a revoluble platen and means for guiding work sheets 125 thereabout, of a quick feed mechanism comprising a driving element having a rotative connection with said platen and an automatic stop mechanism for bringing said platen to rest at the end of a quick feed 130

- movement of predetermined extent by automatically arresting said driving element at an intermediate point in its effective range of movement, said stop mechanism being 5 one way acting and self releasable so as to permit further feeding movement of said driving element and its connected platen in either direction, after thus determining the extent of a quick feed.
- 10 6. The combination with a platen, of a hand-crank for rotating said platen, a plunger carried by said hand-crank, a dog for projecting said plunger, and a stop located in the path of said plunger when projected, 15 and positioned so that said plunger clears said dog when engaging said stop, whereby the rotation of said platen may be temporarily interrupted, to determine a certain spacing of the sheets carried thereby.
- 20 7. The combination with a platen arranged to support and manipulate carbon and work-sheets, of driving means for rotating said platen a number of line-spaces at a time, and one-way acting interrupting 25 means for stopping the continued movement of said platen in one direction inter-
- mediate limits of said rotation, and silent during the rotation of said platen in the other direction, so as to permit an uninterrupted movement between the limits of 30 rotation of the platen.
8. The combination, with a revoluble platen, means for guiding work sheets thereabout and means for line-spacing the same, of a quick feed mechanism comprising a driving element having a rotative connection with said platen and a normally ineffective stop mechanism capable of being rendered effective to arrest said driving element at a predetermined point in its movement when manipulated rapidly to effect a quick feed of said platen, said stop mechanism being one way acting and self releasable at the end of such manipulation to permit further feeding movement of said 40 driving element and its connected platen in either direction after thus determining the extent of a quick feed.
